(57) **CLAIM**

The ornamental design for a cable retaining device for vehicle antenna, as shown and described.

DESCRIPTION

FIG. 1 is a perspective view of a cable retaining device for vehicle antenna showing our new design;

FIG. 2 is a perspective view thereof;

FIG. 3 is a perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is an environmental perspective view of FIG. 1;

FIG. 11 is an environmental perspective view of FIG. 3; and,

FIG. 12 is an environmental perspective view.

The broken lines shown in the drawings illustrate portions of the cable retaining device for vehicle antenna and form no part of the claimed design.
